UNITED STATES PATENT OFFICE.

WILLIAM TAYLOR, OF BUFFALO, NEW YORK.

HANDLE FOR UMBRELLAS, WALKING-CANES, &c.

SPECIFICATION forming part of Letters Patent No. 399,449, dated March 12, 1889.

Application filed August 4, 1888. Serial No. 282,017. (No model.)

To all whom it may concern:

Be it known that I, WILLIAM TAYLOR, of Buffalo, in the county of Erie and State of New York, have invented certain new and useful Improvements in Handles for Walking-Canes, Umbrellas, Parasols, Fishing-Poles, &c.; and I do hereby declare that the following description of my said invention, taken in connection with the accompanying sheet 10 of drawings, forms a full, clear, and exact specification, which will enable others skilled in the art to which it appertains to make and use the same.

This invention has general reference to improvements in handles for canes, umbrellas, parasols, fishing-poles, &c.; and it consists, essentially, in the novel and peculiar combination of parts and details of construction, as hereinafter first fully set forth and described, 20 and then pointed out in the claims.

In the drawings already mentioned, which serve to illustrate my said invention more fully, Figure 1 is an elevation of a walking-cane provided with my improved handle and head. Fig. 2 is a longitudinal sectional elevation of the same in line $\alpha\alpha$ of Fig. 3. Fig. 3 is an elevation at right angles to that shown in Fig. 1. Fig. 4 is a plan, the cover of the compass being shown in an open position. 30 Figs. 5 and 6 are fragmental sections of the compass, showing the device for elevating the magnetic needle to bring it to a position of rest.

Like parts are designated by corresponding letters of reference in all the figures.

35 The object of this invention is the combination, with a walking-cane, umbrella, parasol, fishing-pole, &c., of a handle containing the apparatus necessary for meteorological observations—viz., a storm-glass, thermometer, compass, &c.

To accomplish this result, I construct the head, Λ , of a cane, &c., with a recess, Λ' , engaging a tenon, B' , on the upper end of the handle B , whereby said head is securely affixed to said handle, or otherwise fastened, if desired. In the upper face of this head I form a further recess, into which is inserted a cylindrical shell, G , having a cover, H , suitably hinged at N , said shell G being provided 50 with a magnetic needle, I , balanced upon a pin, M , the bottom of said shell G having the usual compass-dial divided into the different

quarters, hours, minutes, seconds, &c., the same as the usual ship's or mariner's compass. In the cover H , I provide for a portrait, H' , 55 if desired. The magnetic needle is rendered inoperative by means of a lever, J , having an eye, j , on one end, and an upwardly-curved portion, i , on the other end, a slide, k , with an incline, k' , Fig. 5, being arranged to depress 60 the curved end, and thereby to elevate the opposite end, and which also lifts the magnetic needle I , and therefore places the same at rest. The slide k is operated by a knob or handle, L , from the outside of the shell G , as 65 illustrated in the drawings. The handle B is of tubular form and arranged to receive a so-called "storm-glass," D , there being rubber or other suitable cushions, $D'D''$, placed on the ends of said storm-glass to isolate it 70 from the material of which the handle B is made, and thereby to prevent it from being readily broken.

In the handle B there is a longitudinal slot or aperture, E , through which the contents of the storm-glass may be examined and the indications thereof observed and studied. The construction of these storm-glasses is well understood, they being a regular article of commerce. Suffice it to say that they consist of a 80 glass tube nearly filled with a liquid and a salt, a mixture affected by the conditions of the atmosphere, and upon their chemical action, turbidity, &c., certain rules are based, which, it is claimed, foretell changes in the weather, 85 approaching storms, &c. In the face of the handle B is furthermore placed a thermometer, F , indicating the temperature of the atmosphere, said thermometer F being preferably of the glass using mercury, as best 90 adapted to my wants.

It will now be readily observed that the portion C of my device may be a walking-cane, fishing-pole, umbrella-stick, &c., and that the head Λ of my handle may be made of either 95 wood, metal, or other material now used in the art for similar purposes.

The device heretofore described is especially serviceable to tourists, sportsmen, &c., who possess in the handle all the necessary instruments for determining the temperature and other meteorological state of the atmosphere, the direction of the compass, &c. It is also readily applied to umbrella-sticks,

parasols, &c., without change or modification.

It will be further observed that the handle need not be supplied with all the appliances heretofore described. For instance, I may use 5 the compass alone, or the compass with the thermometer, or the storm-glass, without change or modification, such change being readily made and not affecting the nature of my invention.

Having thus fully described my invention, I 10 claim as new and desire to secure to me by Letters Patent of the United States—

1. As an improved article of manufacture, a handle for a walking-cane, umbrella, parasol, fishing-pole, and the like, consisting of a 15 head, A, having the compass with its cover H, the hollow body portion B, provided in its bore with the storm-glass D, and the slotted

aperture E, and the thermometer F, the whole being combined and arranged in a manner 20 as and for the purpose stated.

2. The combination, with the head A, of the shell G; having the cover H, the central pin, M, magnetic needle I, and the lifter J, provided with a suitable handle, L, as and for 25 the object set forth.

3. In handles for canes, umbrellas, and the like, the combination, with the central portion, B, having a core, C', of a storm-glass, D, retained in position by the elastic cushions 30 D' D'', said portion B having a longitudinal slot, E, as and for the object stated.

WILLIAM TAYLOR.
